UNITED STATES PATENT OFFICE.

HENRY M. WILLIS, OF HEMPSTEAD, NEW YORK.

DESIGN FOR A STICK-PIN.

No. 39,867.

Specification for Design.

Patented March 9, 1909.

Application filed January 9, 1909. Serial No. 471,535. Term of patent 7 years.

To all whom it may concern:

Be it known that I, HENRY M. WILLIS, a citizen of the United States, residing in Hempstead, county of Nassau, and State of New York, have invented a new, original, and ornamental Design for Stick-Pins, of which the following is a specification, reference being had to the accompanying drawing, forming part thereof.

The drawing shows my design for pin in front elevation, said design consisting of an elongated body-portion 1, surmounted by a head 2, in the form of a horseshoe connected symmetrically to said body-portion by means of lateral branches or connecting portions 3, extending from the end of the said body-portion 1 in such manner as to permit the

ends of the horseshoe to depend on opposite sides of the said body-portion. Near its lower end, the body-portion 1 is provided with a lateral extension or lug in the form of a swastika 4, the latter being secured to the said body-portion by one of its branches 5. The general appearance thus given to my design is that of a novel and ornamental form of key.

I claim:

The ornamental design for a stick pin, as shown and described.

HENRY M. WILLIS.
